RAILWAY CAR DRAFT GEAR

Hubert L. Spence, East Cleveland, Ohio, assignor
to National Malleable and Steel Castings Company, Cleveland, Ohio, a corporation of Ohio

Application July 19, 1943, Serial No. 495,239

6 Claims. (Cl. 213—36)

1

The Association of American Railroads during the past several years has adopted certain standards of freight car construction, including standard dimensions for draft gears and for the pocket in the underframe of the car within which the gear must operate. An A. A. R. draft gear must conform to the following dimensions: $9\frac{1}{2}$ " maximum by $12\frac{3}{4}$ " maximum by $24\frac{5}{8}$ " long, including the follower. The travel or stroke of the draft gear must be between $2\frac{1}{2}$ " and $2\frac{3}{4}$ ". Certain standards for draft gear performance have been adopted which among other things call for a minimum capacity of 18,000 foot-pounds when tested under the 27,000-lb. drop hammer. Several makes of draft gears conforming in all respects to the A. A. R. specifications are on the market and it has been found that they protect the car satisfactorily from the buffing and pulling shocks incident to train operation, switching and classification yards. There has, however, been a steady improvement in the handling of freight cars, due to improved air brakes, better mechanical equipment in classification yards as well as to lighter weight car design utilizing high tensile steels. In recent years the tight lock coupler has come into general service on passenger train equipment and there is a growing tendency to use a tight lock coupler or one with a greatly reduced amount of free slack for freight service. The use of any such coupler will still further improve the handling of cars and will serve to reduce the shocks which now have to be cushioned by the draft gear.

The elimination or any substantial reduction in free slack in couplers will increase the problem of starting long, heavy trains. It would probably be impossible to start a heavy train with present existing locomotives if all cars in that train had to start into motion simultaneously. The free slack existing in present couplers plus the relatively slight yield or compression afforded by the draft gears under the starting tractive effort of the locomotive, allows the cars to be started into motion serially. There is at the present time approximately $2\frac{1}{2}$ " of relative movement between adjacent cars when subjected to the starting tractive effort of the average freight locomotive. This is made up of 1" free slack between couplers and approximately $1\frac{1}{2}$ " of movement in the two draft gears (that is, $\frac{3}{4}$ " movement per gear). This has been found sufficient to produce the necessary serial action in the starting of the cars of the train.

However, if tight lock couplers were to be used (in which all coupler slack has been eliminated),

2

or if a substantial reduction in free slack is made, it would be necessary to provide a softer draft gear action in response to the starting tractive effort of the locomotive in order to secure the necessary serial action for starting the train. This softer draft gear action would, however, reduce the cushioning or shock absorbing capacity of the draft gear, both under buffing shock as well as under pulling action. It is not desirable, however, to make any reduction in the buffing capacity of draft gears of the present type, for the reason that it is well known that the buffing shocks to which a draft gear is subjected are more severe than the pulling or draft shocks.

15 It is believed that the pulling capacity of a draft gear can safely be reduced to the extent necessary to produce the softer starting action.

I am aware that many attempts have been made to increase the buffing capacity as compared with the draft or pulling capacity of draft gears. Some of these attempts involve a preliminary spring action in pulling, while others involve draft gears with two friction systems, one system working in pulling and the other (or both systems) working in buff. These draft gears so far as I am aware all involve non-standard car construction and non-standard draft attachments with considerable increase in weight. Their use has therefore been very restricted.

20 30 The purpose of this invention is to produce a draft gear of A. A. R. standard dimensions and adapted for use in standard car construction and with standard draft attachments, and which will produce in buffing the full capacity required by A. A. R. specifications, but which in draft will produce a somewhat softer action to provide sufficient additional yielding slack to enable the starting of trains when the cars are equipped with tight lock couplers or with couplers having a substantially reduced amount of free slack.

35 40 The starting tractive effort of the average main-line freight locomotive is about 80,000 lbs. This is too great to be resisted by springs alone without considerably exceeding the dimensions of the present standard draft gear pocket. It is therefore necessary to make use of a combination of spring and friction.

45 50 In the standard A. A. R. vertical yoke draft rigging chosen for the illustration of the present invention, the inner or rearmost end of the draft gear moves relatively to the rear draft lugs in pull but does not move relatively to them in buff. Between the front or outermost end of the gear and the front draft lugs there is relative motion in buff but not in draft. In all other forms of

A. A. R. draft rigging there is relative movement between one end of the gear and some part of the car or the draft attachment (including the yoke) in pulling but not in buffing, and in my invention I make use of this selective relative movement as the means to make possible a softer gear action in pull than in buff.

In the drawings:

Figure 1 is a plan view partly in section, showing a draft gear embodying my invention.

Figure 2 is a view similar to Figure 1, showing the draft gear in buff position; and

Figure 3 is a view similar to Figure 1, showing the draft gear in pulling position.

In the form chosen for illustration I have shown the A. A. R. vertical yoke application in which the rear draft lugs are shown at 1, the front draft lugs at 2, these lugs being secured to the draft sills 3. The front end of the vertical yoke which receives the shank of the coupler is shown at 4 and the rear part of the yoke which engages the draft gear in pulling is shown at 4a.

The draft gear to which this invention has been applied is one of the well known types and consists of a follower wedge 5, friction shoes 6, which are wedged against a central friction member 7, and forced along the friction member in frictional contact therewith. The movement of the friction shoes along the central friction member is resisted by two sets of double coil springs, indicated at 8, transmitting their pressure against the friction shoes through a segment seat or follower 9. The amount of frictional resistance developed between the friction shoes and the friction member is roughly proportional to the pressure with which these springs force the shoes into the follower wedge 5.

When the gear is assembled to its normal length and inserted into the gear pocket, these springs are compressed slightly so as to maintain the friction parts tight and to compensate for any wear which may develop. In my invention I make the inner coil of each spring shorter than the outer coil, with its innermost end (the end away from the coupler) seated against a plunger 10.

Figure 2 shows the draft gear partly compressed in buffing. The forward end of the gear has been forced away from the front draft lugs and the wedge has moved the friction shoes along the central friction member, compressing both inner and outer coils of the springs 8. In this action the plungers 10 as well as the rear or base of the draft gear bear directly against the rear draft lugs 1, thus compressing both coils of the springs 8 and forcing the friction shoes into normal frictional contact with the friction member, thus producing normal buffing action.

Figure 3 shows the draft gear under partial compression in pulling. The back portion 4a of the yoke engages the base of the draft gear and pulls it away from the rear draft lugs, while the forward end of the gear is held from movement by contact with the front draft lugs. This action compresses the outer coils of the springs but the plungers 10 being free to move relatively to the base of the gear, remain in contact with the rear draft lugs. Thus, during this part of the pulling movement the inner coils of the springs are not compressed, with the result that the spring pressure against the friction shoes does not build up as rapidly in pulling action as it does in the buffing action illustrated in Figure 2.

After a predetermined amount of pulling movement the flange 10a on the plunger comes into

contact with the base of the draft gear and thus limits further movement of the base relative to the plunger. At that point the plunger is forced to move with the base of the gear, thus compressing the inner coils of the springs, during the remainder of the pulling movement of the draft gear. During the release movement of the parts the outer coils of the springs force the friction member and base of the gear back to a fully released position in contact with the rear draft lugs.

Thus, it will be seen that under buffing action both the inner and the outer spring coils are compressed during the entire buffing movement of the draft gear. Under pulling action the outer coils are compressed during the entire pulling movement, whereas the inner coils are not compressed until a predetermined point has been reached in the pulling movement of the gear. Thus, the spring pressure forcing the shoes into the follower wedge is reduced during the pulling movement of the gear as compared with the buffing movement, and consequently the resistance offered by the gear in pulling is decreased or softened as compared with its normal buffing resistance.

It is obvious that this invention may be applied to other types of gears in which the gear capacity is determined by the capacity of the springs which set up the frictional action. In the present instance I have made use of the relative movement in pulling action between the inner end of the draft gear and the rear draft lugs.

It is obvious that similar use may be made of the relative movement between the coupler butt 35 and draft gear in pulling, or the relative movement between the draft gear and other parts of the attachments or the car structure which exists in pulling but not in buffing.

The terms and expressions which I have employed are used as terms of description and not of limitation, and I have no intention, in the use of such terms and expressions, of excluding any equivalents of the features shown and described or portions thereof, but recognize that various modifications are possible within the scope of the invention claimed.

What I claim is:

1. A railway draft gear comprising a pair of relatively movable followers, spring means between said followers, a friction system, certain of said spring means actuating said friction system throughout relative movement of said followers in draft and buff, stop means at one end of said draft gear, and means in engagement with others of said spring means and with said stop means adapted to actuate said friction system after a predetermined amount of relative movement of said followers in draft.

2. A railway draft gear comprising a wedge, shoes and a friction member, spring means acting on said shoes for urging said shoes into engagement with said wedge and friction member throughout closure of said draft gear in buff and draft, abutment means at one end of said draft gear, and means comprising other spring means between said shoes and said abutment means exerting a constant pressure against said shoes for a part of the closure of said draft gear in draft and movable with said friction member for exerting an increasing pressure against said shoes for the remainder of the closure of said draft gear.

3. A friction draft gear comprising a friction member, a wedge member, a friction shoe interposed between said friction member and wedge

member, spring means reacting at one end on said shoe for urging said member and shoe into frictional contact, abutment means engaging the other end of said spring means and slidably associated with said friction member, said abutment means being normally adapted for engagement with the rear draft lug of a car, and means for moving said friction member relatively to said abutment means in draft so as to cause said spring means to act with a constant force against said shoe during a portion of the travel of said gear in draft, said abutment means being adapted to engage the rear draft lug throughout the travel of said gear in buff to cause said spring means to act with increasing force against said shoe during travel of said gear in buff.

4. A friction draft gear comprising a friction system and spring means for actuating said friction system, certain of said spring means acting against said friction system when said draft gear is compressed in buff or draft, abutment means at one end of said draft gear movably associated with said friction system, and others of said spring means engaging said abutment means, said abutment means remaining stationary when said draft gear is compressed a predetermined amount in draft and being movable with said friction system during the remainder of said movement and causing said last-named spring means to act against said friction system with constant force during said predetermined movement in draft and with increasing force during the remainder of said movement.

5. In a railroad car, a draft gear pocket, a friction draft gear within said pocket, a yoke surrounding said draft gear and connected to a car coupler for actuating said gear in draft and buff, spring and friction means in said draft gear, certain of said spring means acting against said friction system and a part of said pocket so as to exert a force against said friction means proportional to the movement of said gear in said pocket in one direction, and spring controlling

means between said draft gear and pocket slidably associated with said draft gear, said last-named means being adapted to move with respect to said draft gear for a part of the travel thereof so as to cause said spring means to exert a force on said friction means an amount not proportional to the movement of said draft gear in the other direction.

6. A friction draft gear comprising a friction member having a base, a friction shoe slidably associated with said member, a wedge member engaging said shoe and movable relative to said member, spring means for resisting movement of said wedge relative to said member, a plunger movable a predetermined amount with respect to said base of said member in a direction lengthwise of the draft gear, the end of said plunger normally engaging the rear draft lug of the draft gear pocket of a railway car, and other spring means reacting between said plunger and said shoe for resisting movement of said shoe relative to said member, said plunger remaining in engagement with said rear draft lug during movement of said plunger with respect to said base said predetermined amount during closure of said gear in draft, thereafter said plunger engaging said base and traveling therewith during further closure of the gear.
